UNITED STATES PATENT OFFICE

2,085,755

SHOE MACHINE

Jacob C. Jorgensen, Beverly, Mass., assignor to
 United Shoe Machinery Corporation, Paterson,
 N. J., a corporation of New Jersey

Application February 14, 1936, Serial No. 63,909

23 Claims. (Cl. 12—126)

This invention relates to machines for use in the manufacture of shoes, and more particularly to means for presenting the work in position to be operated upon in such machines. The invention is herein illustrated as applied to a heel-end lasting machine of the same general character as disclosed in United States Letters Patent No. 2,059,241, granted on November 3, 1936 upon an application of mine, but it is to be understood that the invention is not limited to machines of that particular character or to machines for lasting shoes.

The machine shown in the above-mentioned Letters Patent comprises mechanisms which operate automatically upon a shoe in a cycle of operations of the machine, and a shoe support or jack arranged to be swung by the operator to carry the shoe lengthwise against a heel-end abutment and including a post arranged also to be moved upwardly by the operator to carry the shoe heightwise against a holdown prior to the starting of the cycle of operations. The present invention, in its illustrative embodiment, provides fluid-pressure means for thus swinging the jack and raising the post, thereby not only relieving the operator of the labor required heretofore in presenting the work, but also accelerating this operation and accordingly increasing the output of the machine. The construction herein shown comprises a fluid-operated member movable by pressure of fluid against it, and means for operating the jack and its post to impart the lengthwise and heightwise movements to the shoe by the movement of this member. The swinging of the jack and the lifting of the post are conveniently effected, as heretofore, through mechanism so constructed and arranged that it tends in operation to produce both these results, and the invention further provides novel controlling means for preventing the lifting of the post by this mechanism until the shoe has been carried to a position under the holdown by the swinging of the jack. For better insurance of a proper coordination of the different movements of the shoe, there is also provided means, herein shown as an air check, which by retarding the swinging of the jack insures the lifting of the post by the above-mentioned mechanism as soon as permitted by its controlling means. The retarding action of this air check is preferably so adjusted that the shoe is carried into engagement with the end abutment and the holdown at substantially the same time, thereby avoiding

any objectionable rubbing action of the abutment or the holdown on the shoe.

In the machine shown in the above-mentioned Letters Patent there are included mechanisms which automatically assume control of the jack and its post near the beginning of the cycle of operations of the machine; and preferably, in accordance with a further feature of this invention, the fluid-pressure means is rendered inoperative when these mechanisms become effective. For this purpose the construction herein shown includes means which operates automatically at the required time to disconnect valve mechanism of the fluid-pressure means from a member which operates that mechanism. In accordance with still other features of the invention there are provided novel means for variably determining the speed of the movement of the jack by the fluid-pressure mechanism, novel means whereby the force with which the shoe is controlled by the fluid-pressure mechanism may be somewhat relieved to facilitate adjustment of the shoe, and novel means for initiating return movement of the jack after the operations on the shoe have been completed.

The above and other features of the invention, including various novel details of construction and combinations of parts, will now be more particularly described with reference to the accompanying drawings and pointed out in the claims.

In the drawings,
 Fig. 1 is a view in left-hand side elevation of the lower portion of a heel-end lasting machine of the character disclosed in the previously mentioned Letters Patent with the present invention embodied therein, parts of the structure being broken away;

Fig. 2 is a plan view of a portion of the structure shown in Fig. 1, with parts broken away;

Fig. 3 is a section on the line III—III of Fig. 2;

Fig. 4 is a section on the line IV—IV of Fig. 3;

Fig. 5 is a section on the line V—V of Fig. 2;

Fig. 6 is a section on the line VI—VI of Fig. 1;

Fig. 7 is a section on the line VII—VII of Fig. 1; and

Fig. 8 is a view partly in left-hand side elevation and partly in section showing portions of the shoe support or jack and of other parts in their relation to a shoe presented in position to be operated upon.

As more fully disclosed in the previously mentioned Letters Patent, the machine includes in its organization a heel band 2 (Fig. 8) arranged to embrace the heel end of the shoe and to serve as

an abutment against which the heel-end face of the shoe is forced by movement of the shoe support or jack hereinafter described, and a hold-down 4 arranged to engage the bottom of the heel end of the shoe and against which the shoe is forced upwardly by a part of the jack. The shoe is thus positioned against the heel band and the holdown prior to the initiation of the cycle of power operations of the machine, in which cycle of operations the margin of the heel end of the upper is wiped inwardly over the insole or other shoe bottom part by wipers 8, one of which is shown in Fig. 8, and tacks are driven through the wipers by drivers 9 to fasten the upper in lasted position.

The shoe support or jack includes a heel pin or spindle 10 and a toe rest 12 both carried by a post 14 which is mounted for upward and downward movements in a holder 16 supported on two pins 18 (Fig. 1) for limited swinging movements in directions laterally of the shoe, as fully disclosed in the previously mentioned Letters Patent. Through parts also fully shown and described therein the post 14 at its lower end is controlled by a rod 20 movable upwardly and downwardly in a casting 22 which supports the above-mentioned pins 18, this rod being connected at its lower end to a slide 24 also movable upwardly and downwardly in the casting 22. A flange 26 on the rod 20 determines by engagement with the casting 22 the initial lowered position of the rod and of the post 14, and it is by upward movement of the slide 24 that the post is raised to force the shoe against the holdown 4. When the parts are in their initial positions, however, the shoe is not located beneath the holdown, but forwardly thereof, the casting 22 being for this purpose mounted for swinging movements with the other jack parts about pins 28, one of which is shown in Fig. 1; and before the shoe is raised by the slide 24 it is carried rearwardly toward the heel band 2 and to a position under the holdown by rearward swinging movement of the jack. For determining the initial forwardly inclined position of the jack there is pivotally connected to a pair of upwardly extending arms 30 on the casting 22 a bar 32 which is mounted in a slideway formed in a member 34, this member being mounted to rock about a shaft 36 supported in bearings in the frame for a purpose hereinafter described. Near its rear end the bar 32 carries a pin 38 arranged to engage a shoulder on the member 34 to limit the forward swinging movement of the jack.

The rearward swinging movement of the jack to carry the heel end of the shoe against the heel band 2 and the upward movement of the post 14 to force the shoe against the holdown 4 are effected through a lever 40 fulcrumed on a rod 42 which is mounted on a bracket 44 on the lower end of the jack casting 22. The forward end of this lever bears against the lower end face of the slide 24, and connected to the rear end of the lever is a link 46 for operating it. It will be evident that by reason of the relation of the link 46 to the pins 38 the link by its pull on the lever 40 tends to swing the jack rearwardly about these pins as well as to raise the slide 24 by swinging the lever about its fulcrum 42. These parts are of substantially the same construction as disclosed in the previously mentioned Letters Patent; but whereas in the machine therein shown the link corresponding to the link 46 was operated by a treadle for moving the jack and its post 14 in the manner described, the present in-

vention provides for this purpose automatically operating fluid-pressure means. This fluid-pressure means includes a casting 48 secured to the frame of the machine and serving in part as a container for oil, as hereinafter more fully described. Formed as a part of the casting 48 is a cylinder 50 (Figs. 4 and 5) in which is mounted for upward and downward movements a piston 52. The cylinder 50 communicates at its lower end with an oil chamber 54, and a projection 56 on the lower end of the piston 52 serves by engagement with the lower wall of the chamber 54 to limit downward movement of the piston. The piston 52 at its upper end is in engagement with a rod 58 adjustably threaded in a horizontal arm 60 (Figs. 2 and 5) which is secured to the upper end of a plunger or bar 62 movable vertically in a slideway in the casting 48, the bar being confined in the slideway by a plate 64 fast on the casting. At its lower end the bar 62 is pivotally connected (Fig. 3) to a link 66 which is connected to one arm of a lever 68 (Fig. 1) mounted on a bracket 70 at the base of the machine. The other arm of the lever 68 is connected to the previously mentioned link 46. It will thus be seen that upward movement of the piston 52 serves to raise the bar 62 and thereby to swing the lever 68 in the direction to pull downwardly on the link 46 to swing the jack and raise the slide 24 and the post 14 as hereinbefore described.

In order to insure against raising the post and the shoe until the shoe is located under the holdown 4, there is provided by this invention means which prevents swinging movement of the lever 40 about its fulcrum rod 42 until the jack has been swung rearwardly far enough to carry the heel end of the shoe to a position under the holdown. This means comprises a control block 72 (Figs. 1 and 6) having a curved face 74 concentric with the axis of swinging movement of the jack and engaged by a roll 76 on the rear end of the lever 40. The block 72 is slidably movable along a guideway on a bracket 78 fast on the base of the machine and is controlled by a crank pin 80 formed on one end of a shaft 82 which is mounted in a bearing in the bracket 78 and in another bearing in the frame. A plate 84 (Fig. 6) fast on the frame and engaging a shoulder on the shaft 82 assists in holding the shaft against lengthwise movement. Fast on the reduced outer end of the shaft is a knob 86 for turning it, its turning movement being limited by a stop screw 88 mounted in the frame and extending through a slot 90 in the hub of the knob 86, this slot being indicated by dotted lines in Fig. 6. It will be understood that by turning the knob 86 the block 72 is adjusted through the crank pin 80 to vary the time when the roll 76 is released by the block to permit upward movement of the slide 24.

For better insurance that the shoe will not be forced rearwardly against the heel band before it is raised by the lever 40, there is provided an air check comprising a piston 92 (Fig. 1) operating in a cylindrical chamber 94 formed in the member 34 in which the bar 32 is slidably mounted as hereinbefore described, the piston being formed on one end of a rod 96 the other end of which is connected to the bar 32. Air is permitted to escape from the chamber 94 through a port 98 (Fig. 7), the escape of the air being restricted and controlled by a valve 100. A spring 102 tends to force the valve 100 toward a conical seat provided therefor in the member 34, but the valve is held slightly open by a finger 104 75

in engagement therewith, this finger being formed on a screw 106 adjustably threaded in the member 34. Air escaping past the valve 100 passes through an opening 108 in the member 34. It will be understood that by adjusting the valve 100 by means of the screw 106 the cushioning effect of the air check may be varied. The resistance of the air check to the swinging of the jack, which is especially effective near the end 10 of the swinging movement, insures that the lever 40 will begin to raise the post 14 as soon as permitted by the block 72 while the swinging of the jack continues, the valve 100 being preferably so adjusted that the shoe is carried into engagement with the heel band and the holdown at substantially the same time.

To initiate the return movement of the jack so that the remainder of its movement may be completed by gravity there is provided a bell-crank lever 110 (Figs. 1 and 3) mounted for swinging movement on a bracket 112 on the frame and having on one arm thereof a roll 114 arranged to rest on the upper end of the bar 62. A spring 116 connected to the bell-crank lever 25 and to a finger 118 on the plate 64 tends to swing the bell-crank lever in a counterclockwise direction. It is swung in the opposite direction against the resistance of this spring by the upward movement of the bar 62 to operate the jack 30 and its post 14. One arm of the bell-crank lever has a rounded end 120 arranged to engage the head of a rod 122 horizontally movable in the frame of the machine but limited in its forward movement by engagement of its head with the 35 frame. At its forward end this rod is arranged to engage a plate 124 on the jack. When the jack is released near the end of the cycle by means hereinafter described, the bell-crank lever 110 is swung by the spring 116 and acts through the 40 rod 122 to push the jack forwardly to such a position that the remainder of its forward movement will be readily effected by gravity.

In addition to the chamber 54 the casting 48 is provided with two other chambers 126 and 128. The chamber 126 is partially filled with fluid, preferably oil, and has two covers 130 and 132 through several openings in which this chamber is in communication with the atmosphere. The oil is drawn from the chamber 126, through a 50 strainer 134 and a pipe 136, by a continuously operating gear pump 138 (Fig. 1) which is operated through a pulley 140 by a belt 142 driven by another pulley, not herein shown, fast on a shaft corresponding to the shaft 756 shown in 55 the previously mentioned Letters Patent. The oil is forced by the pump 138 through a pipe 144 into the chamber 128, this pipe having thereon a pressure gage 146. From the chamber 128 the oil is conducted either to the chamber 54 to operate the piston 52 or back to the main chamber or reservoir 126, as determined by valve mechanism 60 movable by the operator. This valve mechanism comprises a sleeve 148 (Figs. 3 and 5) movable upwardly and downwardly in a casing 150 secured within the casting 48. The casing 150 is provided with ports 152 which communicate with the chamber 128, and with other ports 154 which communicate with the chamber 54. Formed in the sleeve 148 are ports 156 arranged 65 to communicate with the ports 152 in the casing 150, ports 158 which communicate with the ports 154 in this casing, and other ports 160 arranged to communicate with the chamber 126. Ordinarily, as shown in Figs. 3 and 5, the chamber 128 70 is in communication with the chamber 126

through the ports 152, 156 and 160, so that the oil is circulated continuously by the pump with comparatively little pressure in the chambers 128 and 54. The ports 160 in the sleeve 148 are controlled by a piston 162 which is movable upwardly in the sleeve to close these ports and thereby to shut off communication with the chamber 126, so that the pressure of the oil in the chamber 54 is increased to operate the piston 52. The piston 162 is formed on the lower end of a rod 164 which has also formed thereon another piston 166 located in the sleeve 148 above the ports 156. Located between the piston 166 and a head 167 on the upper end of the sleeve 148 is a compression spring 168 which tends to move 15 the rod 164 and the piston 162 downward relatively to the sleeve, such downward movement being limited by the engagement with the head 167 of the socketed lower end of another rod 170 fast on the upper end of the rod 164. Fast on 20 the rod 170 is a thimble 172 which extends loosely through an opening in the cover 132 and is connected to an arm 174 to which upward movement may be imparted by a vertically movable bar 176 25 slidingly mounted in the casting 48. The arm 174 is forked to receive a reduced portion of the thimble 172 and imparts upward movement to the rod 170 through a spring 178 which bears at its lower end on a washer 180 engaged by the arm 174 and at its upper end on a washer 182 engaged 30 by a pin 184 on the rod 170. Upward movement of the rod 170 and of the piston 162 is limited by engagement of a flange 185 on the piston with the lower end of the sleeve 148, after which the spring 178 will yield in response to any further 35 upward movement of the arm 174. The bar 176 is connected to the arm 174 by a latch 186 pivoted at 188 on the arm and held in a notch in the bar by a spring 190 connected at its lower end to a pin 192 fast in the plate 64. This pin extends 40 into a slot 194 in the bar 176 to limit the upward movement of the bar. At its lower end the bar 176 is pivotally connected by a pin 196 to the upper end of a link 198 the lower end of which is connected to a treadle 200 pivotally mounted on 45 the bracket 70. It will thus be seen that when the operator depresses the treadle 200 the bar 176 is raised and acts through the latch 186 to raise the arm 174, the arm acting through the spring 178 to raise the piston 162 and thereby 50 close the ports 160 in the sleeve 148 to cause the piston 52 to be raised by the fluid pressure means to operate the jack and its post 14 as hereinbefore described. A spring 202 connected to the pin 196 serves to lower the bar 176 and return 55 the treadle when the operator removes his foot from the treadle.

Reference has been made to the fact that the sleeve 148 is movable upwardly and downwardly in the casing 150. The normal position of the sleeve relatively to the casing is determined by engagement of the head 167 on the sleeve with the upper end of the casing, and from this position the sleeve is raised by the rod 164 through the spring 168 only a sufficient distance to effect 60 a partial closure of the ports 156 before the piston 162 begins to move upward relatively to the sleeve. Such upward movement of the sleeve 148 is variably limited by means including a rod 204 slidingly movable vertically in a bracket 206 65 fast on the casting 48 and having an enlarged lower end arranged to engage the head 167 of the sleeve. At its upper end the rod 204 is engaged by a member 208 pivotally mounted on the bracket 206, and this member is arranged to en- 70 75

gage the end of a screw 210 threaded in the bracket. It will be understood that the screw 210 adjustably limits the amount of movement of the member 208 and accordingly the amount 5 of upward movement of the sleeve 148 to determine the amount of opening of the ports 156 through which the oil must pass to the chamber 54. In this manner the speed of the movement 10 of the jack by the fluid-pressure means is adjustably determined. The screw 210 is conveniently adjusted by the operator by means of a knob 212 (Fig. 1) fast on a shaft 214 mounted in a bearing in the frame. This shaft is connected by a universal joint 216 to a shaft 218 15 slidingly mounted in a sleeve 220 which is fast on another shaft 222 connected by a universal joint 224 to the screw 210. By reference to Fig. 2 it will be seen that the shafts 218 and 222 have flat faces in engagement with each other for 20 operating the shaft 222 by the turning of the shaft 218.

After the shoe has been forced upwardly 25 against the holdown 4 by the fluid-pressure means, the operator may desire to adjust it relatively to the holdown, as by tipping it laterally, before starting the power operation of the machine, and to facilitate such adjustment of the shoe it is desirable to relieve somewhat the pressure with which it is held against the holdown 30 and the heel band. For this purpose the piston 162 (Fig. 3) and a portion of the rod 164 immediately above the piston are hollow, this portion of the rod being provided with small ports 226 to permit some of the oil under pressure to enter 35 the hollow piston. The piston 162 also is provided with ports 228 leading outwardly to a portion of the piston which is of reduced diameter and which permits escape of the oil from the piston through the ports 169 to the chamber 126 40 when the piston is lowered slightly from the position which it normally occupies when the jack is being operated upon by the fluid-pressure means. The rate at which the oil is thus permitted to escape is controlled by a valve 230 45 threaded in the piston 162 and having a conical upper end restricting the flow of the oil from the hollow portion of the rod 164. The short downward movement of the piston 162 to relieve the pressure with which the shoe is held against the holdown occurs in response to the action of the 50 spring 168 when the operator permits a short reverse movement of the treadle 200. Thereafter the operator again fully depresses the treadle to cause the shoe to be pressed against the holdown by the full force of the fluid-pressure means.

The amount of pressure applied by the oil to the piston 52 to force the shoe against the heel band and the holdown is determined by a pressure control valve 232 vertically movable in a 55 casing 234 fast on the casting 48. This valve has ports 236 arranged to communicate with an annular recess 238 in the casing 234 when the valve is raised by pressure of the oil in the chamber 128, the annular recess 238 communicating with the chamber 126 through ports 240. It will thus be seen that when the valve is raised by pressure of the oil a by-pass is afforded for the oil from the chamber 128 to the chamber 126. When 60 the oil is thus permitted to escape from the chamber 128 it is nevertheless maintained under a predetermined pressure in this chamber and in the chamber 54 by reason of the fact that the valve 232 is controlled by a spring 242 against 65 the resistance of which it is raised by the pres-

sure of the oil. This spring is mounted on a rod 244 extending upwardly through an opening in a plug 246 threaded in the upper end of the casting 234, the opening being somewhat larger than the rod to permit escape of air above the valve 232 when the valve is raised. The spring 242 bears at its lower end upon a conical head formed on the rod and engaging the valve 232, and bears at its upper end on two centralizing members 248 having curved recesses to engage the rod 244 10 and outer curved faces in engagement with the wall of a conical recess in the plug 246. The two members 248 are separated by a sufficient space to permit escape of air from above the valve, and they serve to maintain the rod 244 in a 15 central position in the opening in the plug 246 without permitting it to rattle by contact with the plug. It will be understood that by turning the threaded plug 246 the amount of compression of the spring 242 may be varied to vary the pressure of the oil in the chambers 54 and 128 and accordingly the force with which the shoe is 20 pressed against the heel band and the holdown.

While the operator holds the treadle 200 depressed with the shoe pressed against the heel band and the holdown by the fluid-pressure means, he starts the cycle of operations of the machine by tripping the clutch in the manner disclosed in the previously mentioned Letters Patent. In this cycle of operations control of 30 the jack is assumed and maintained by automatic means which not only holds the shoe against the heel band and the holdown but serves to increase the pressure of the shoe against these parts. For this purpose there is provided 35 pawl-and-ratchet mechanism (not herein shown) acting through a pinion 250 (Fig. 1) to control the bar 32 for swinging the jack and other pawl-and-ratchet mechanism acting on a lever 252 connected to the slide 24 for controlling the jack 40 post 14. These pawl-and-ratchet mechanisms and parts associated therewith are fully shown and described in the above-mentioned Letters Patent. They are operated respectively by levers 254 and 256 to which operative movements are 45 imparted near the beginning of the cycle by the turning of a member 258 in a counterclockwise direction (Fig. 1), this member corresponding to the member 194 shown in the above-mentioned Letters Patent. In order that the jack and its 50 post 14 may be controlled solely by these pawl-and-ratchet mechanisms after they become effective, there is provided mechanism for rendering the fluid-pressure means inoperative by swinging the latch 186 (Fig. 3) into position to disconnect the arm 174 from the bar 176. The latch is provided with an arm 260 (Figs. 2 and 3) which carries a pin 262 extending into a slot 264 in a link 266, this link being connected at its upper end to the member 258. When the arm 174 is 55 raised by the treadle the pin 262 is carried upwardly to a position near the upper end of the slot 264, and when the member 258 receives its counterclockwise movement, which occurs near the beginning of the cycle of operations, the link 60 266 is moved downwardly and acts on the pin 262 to swing the latch 186 out of the notch in the bar 176. The arm 174 is thus released for downward movement, and accordingly the valve parts controlled by the treadle are restored to their 65 initial positions by the springs 168 and 190 to permit free circulation of the oil.

In the use of the machine constructed as described the operator mounts a shoe on the jack and then depresses the treadle 200, thereby rais- 75

ing the bar 176 to the limit determined by the pin 192 and the slot 194. In this operation the rod 170 of the valve mechanism is lifted by the arm 174 and acts first through the spring 168 to lift the valve sleeve 148 to the position adjustably determined by the screw 210 controlling the members 204 and 208. This provides an adjustably restricted passage for the oil through the ports 156 to determine the speed of movement of the jack. As the arm 174 continues its upward movement it acts to raise the piston 162 to the limit determined by engagement of the flange 185 on the piston with the lower end of the sleeve 148, after which the spring 178 yields in response to any further upward movement of the arm. The ports 160 are thus closed by the piston 162 to interrupt the circulation of the oil, so that the pressure of the oil in the chamber 54 is increased and acts to raise the piston 52. By such upward movement of the piston 52 the bar 62 is raised to swing the jack rearwardly through the connections 66, 68, 46 and 40 to carry the shoe against the heel band. As soon as the lever 40 is released by the member 72 in this swinging movement of the jack this lever is also swung about its fulcrum rod 42 to raise the jack post 14 and carry the shoe against the holdown in the manner hereinbefore described. The pressure with which the shoe is forced against the heel band and the holdown is determined by the control valve 232 which is raised against the resistance of the spring 242 until its ports 236 afford an outlet for the oil. If the operator should desire to adjust the shoe relatively to the holdown after it has thus been presented, he permits a short retractive movement of the treadle in response to which the piston 162 is lowered enough to provide a restricted outlet for the oil through the ports 226 and 228, thus relieving the pressure with which the shoe is held against the holdown and the heel band. By the above-mentioned upward movement of the bar 62 the bell-crank lever 110 is swung against the resistance of its spring 116, so that the rod 122 will permit the required rearward swinging movement of the jack.

After the shoe has thus been presented against the heel band and the holdown by the fluid-pressure means the operator starts the cycle of operations of the machine. Early in the cycle the pawl-and-ratchet mechanisms hereinbefore referred to assume control of the jack and of its post 14 in response to turning movement of the member 258 (Fig. 1) in a counterclockwise direction. In response to the movement of this member the link 266 acts on the latch 186 to release the arm 174 from the bar 176, thus permitting the valve sleeve 148 and its piston 162 to be returned to their initial positions by the spring 190. The pressure of the oil in the chamber 54 is thus relieved, permitting the piston 52 and the bar 62 to be moved downward by gravity. By such downward movement of the bar 62 the lever 40 is swung about its fulcrum rod 42 to such a position that its roll 76 will again meet the face 74 of the member 72 when the jack is swung forwardly. The bell-crank lever 110 remains in the position to which it was previously moved by the bar 62 until the jack and its post 14 are released by the pawl-and-ratchet mechanisms near the end of the cycle, whereupon the spring 116 acts through the bell-crank lever and the rod 122 to initiate the forward swinging movement of the jack.

Having described the invention, what I claim

as new and desire to secure by Letters Patent of the United States is:

1. In a shoe machine, the combination with means for operating on a shoe, of a shoe support mounted for swinging movement to carry a shoe lengthwise toward said operating means and including a member movable relatively to other portions of the swinging support for moving the shoe also heightwise to present it to said means, and fluid-pressure mechanism for swinging said support and for operating said member. 5

2. In a shoe machine, the combination with power-driven means for operating on a shoe in a cycle of operations of the machine, of an abutment for engaging an end of the shoe, a holdown 15 for engaging the bottom of the shoe, a jack mounted for swinging movement to carry the shoe against said abutment and including a member movable relatively to other portions of the jack for moving the shoe heightwise against said holdown, and fluid-pressure mechanism arranged to be actuated to swing said jack and to operate said member prior to the starting of the cycle of operations of the machine. 20

3. In a shoe machine, the combination with 25 means for operating on a shoe, of a jack mounted for movement to carry a shoe lengthwise toward said operating means and including a post movable relatively to other portions of the jack to impart also a heightwise movement to the shoe, 30 a member arranged to be operated by pressure of fluid against it, and connections for operating said jack and post to impart the lengthwise and heightwise movements to the shoe by the movement of said member. 35

4. In a shoe machine, the combination with means for operating on a shoe, of a jack mounted for swinging movement to carry a shoe lengthwise toward said operating means and including a post upwardly movable relatively to other portions of the jack to raise the shoe, a lever mounted on the jack for lifting said post, a member connected to said lever for operating it, said lever and member being so arranged relatively to the jack as also to cause the jack to be swung by the movement of said member, and fluid-pressure mechanism for operating said member. 40

5. In a shoe machine, the combination with means for operating on a shoe, of a jack mounted for swinging movement to carry a shoe lengthwise toward said operating means and including a post upwardly movable relatively to other portions of the jack to raise the shoe, a lever mounted on the jack for lifting said post, a member connected to said lever for operating it, said lever and member being so arranged relatively to the jack as also to cause the jack to be swung by the movement of said member, a device movable in response to pressure of fluid against it to operate said member, a pump for supplying fluid under pressure, and valve means for rendering the fluid supplied by said pump effective to operate said device. 50

6. In a shoe machine, the combination with means for operating on a shoe, of a jack mounted for swinging movement to carry a shoe lengthwise toward said operating means and including a post upwardly movable relatively to other portions of the jack to raise the shoe, a lever fulcrumed on the jack for lifting said post, a member connected to said lever for operating it, said lever and member being so arranged relatively to the jack as also to cause the jack to be swung by the movement of said member, and means for preventing the lever from swinging about its ful- 70

crum to lift the post until after the jack has been swung a predetermined distance by said member.

7. In a shoe machine, the combination with means for operating on a shoe, of a jack mounted for swinging movement to carry a shoe lengthwise toward said operating means and including a post upwardly movable relatively to other portions of the jack to raise the shoe, a lever fulcrumed on the jack for lifting said post, a member connected to said lever for operating it, said lever and member being so arranged relatively to the jack as also to cause the jack to be swung by the movement of said member, and a device arranged to act on said lever to prevent it from swinging about its fulcrum to lift the post until after the jack has been swung a predetermined distance and then to release the lever, said device being adjustable to vary the time when the lever is thus released.

20 8. In a shoe machine, the combination with means for operating on a shoe, of a jack mounted for swinging movement to carry a shoe lengthwise toward said operating means and including a post upwardly movable relatively to other portions of the jack to raise the shoe, mechanism connected to the jack and tending in operation both to swing the jack and to lift said post, and a device for controlling said mechanism to prevent it from lifting the post until after the jack has been swung a predetermined distance.

9. In a shoe machine, the combination with means for operating on a shoe, of an abutment for engaging an end of the shoe, a holdown for engaging the bottom of the shoe, a jack mounted for swinging movement to carry the shoe lengthwise to a position under said holdown and against said abutment and including a post upwardly movable relatively to other portions of the jack to carry the shoe against the holdown, mechanism connected to the jack and tending in operation both to swing the jack and to lift said post, and a device for controlling said mechanism to prevent it from lifting the post until after the jack has been swung far enough to carry the shoe under the holdown.

45 10. In a shoe machine, the combination with means for operating on a shoe, of an abutment for engaging an end of the shoe, a holdown for engaging the bottom of the shoe, a jack mounted for swinging movement to carry the shoe lengthwise to a position under said holdown and against said abutment and including a post upwardly movable relatively to other portions of the jack to carry the shoe against the holdown, mechanism connected to the jack and tending in operation both to swing the jack and to lift said post, a device for controlling said mechanism to prevent it from lifting the post until after the jack has been swung far enough to carry the shoe under the holdown, and means for retarding the swinging of the jack to insure lifting of the post by said mechanism as soon as permitted by said device.

60 11. In a shoe machine, the combination with means for operating on a shoe, of an abutment for engaging an end of the shoe, a holdown for engaging the bottom of the shoe, a jack mounted for swinging movement to carry the shoe lengthwise to a position under said holdown and against said abutment and including a post upwardly movable relatively to other portions of the jack to carry the shoe against the holdown, a lever mounted on the jack for lifting said post, a member connected to said lever for operating it, said lever and member being so arranged rela-

tively to the jack as also to cause the jack to be swung by the movement of said member, a device arranged to prevent said lever from swinging to lift the post until after the jack has been swung far enough to carry the shoe under the holdown, and an air check for retarding the swinging of the jack to insure movement of said lever to lift the post as soon as permitted by said device and before the shoe is carried into engagement with said abutment.

10 12. In a shoe machine, the combination with means for operating on a shoe, of a jack mounted for movement to carry a shoe lengthwise toward said operating means and including a post movable relatively to other portions of the jack to impart also a heightwise movement to the shoe, a member arranged to be operated by pressure of fluid against it for operating said jack and post to impart the lengthwise and heightwise movements to the shoe, a continuously operating pump for effecting a circulation of fluid, valve means for interrupting the circulation of the fluid to cause an increase in the pressure of the fluid against said member, and a pressure control valve arranged to permit escape of fluid when a predetermined pressure is attained to determine the amount of force applied to said member.

20 13. In a shoe machine, the combination with means for operating on a shoe, of a shoe support movable to present a shoe to said operating means, a device movable by pressure of fluid against it for thus moving said shoe support, a source of supply for the fluid, and valve mechanism for controlling the fluid, said valve mechanism comprising a member movable to render the fluid effective to operate said device and another member movable to an adjustably predetermined position in time relation to the movement of said first-named member to afford a variably restricted passage for the fluid and thereby to determine the speed of the movement of the shoe support by said device.

30 14. In a shoe machine, the combination with means for operating on a shoe, of a shoe support movable to present a shoe to said operating means, a device movable by pressure of fluid against it for thus moving said shoe support, a source of supply for the fluid, and valve mechanism for controlling the fluid, said valve mechanism comprising a member movable to render the fluid effective to operate said device and another member movable to an adjustably predetermined position to afford a variably restricted passage for the fluid and thereby to determine the speed of the movement of the shoe support by said device, and a connection common to both said members for operating them.

40 15. In a shoe machine, the combination with means for operating on a shoe, of a shoe support movable to present a shoe to said operating means, a device movable by pressure of fluid against it for thus moving said shoe support, a source of supply for the fluid, and valve mechanism for controlling the fluid, said valve mechanism comprising a sleeve member having ports therein and a piston movable relatively to said sleeve member to render the fluid effective to operate said device, the sleeve member also being movable to an adjustably predetermined position each time the piston is thus operated to afford a variably restricted passage for the fluid and thereby to determine the speed of the movement of the shoe support by said device.

50 16. In a shoe machine, the combination with

- means for operating on a shoe, of a shoe support movable to present a shoe to said operating means, a device movable by pressure of fluid against it for thus moving said shoe support, a continuously operating pump for effecting a circulation of fluid, valve mechanism comprising a sleeve member having a port therein through which the fluid is thus circulated and a piston movable to close said port to interrupt the circulation of fluid and cause the fluid to operate said device, said sleeve member having another port therein through which the fluid passes, and means for imparting to said sleeve member each time said piston is operated an adjustably variable movement to effect a partial closure of said last-named port and thereby determine the speed of the movement of the shoe support by said device.
17. In a shoe machine, the combination with means for operating on a shoe, of a holdown for engaging the shoe, a shoe support movable to force the shoe against said holdown, a device movable by pressure of fluid against it for thus moving said shoe support, a source of supply for the fluid, valve mechanism for controlling the fluid, and a controlling member for moving said valve mechanism to render the fluid effective to operate said device, said valve mechanism having a restricted passage for the fluid arranged to open fully in response to a short retractive movement of said controlling member to relieve the pressure of the shoe on the holdown while the shoe is still maintained in contact with the holdown by the fluid-operated device.
18. In a shoe machine, the combination with means for operating on a shoe, of a holdown for engaging the shoe, a shoe support movable to force the shoe against said holdown, a device movable by pressure of fluid against it for thus moving said shoe support, a continuously operating pump for effecting a circulation of fluid, valve mechanism comprising a sleeve member having a port therein through which the fluid is thus circulated and a piston movable to close said port to interrupt the circulation of fluid and cause the fluid to operate said device, and a controlling member movable to operate said piston, the piston having a restricted passage through it for the fluid arranged to communicate with said port in response to a short retractive movement of said controlling member to relieve the pressure of the shoe on the holdown while the shoe is still maintained in contact with the holdown by the fluid-operated device.
19. In a shoe machine, the combination with power-driven means for operating on a shoe in a cycle of operations of the machine, of a shoe sup-
- port movable to present a shoe to said operating means, fluid-pressure means for thus moving the shoe support prior to the starting of the cycle of operations of the machine, mechanism for controlling the shoe support in the cycle of operations, and automatic means for rendering the fluid-pressure means inoperative near the beginning of the cycle.
20. In a shoe machine, the combination with power-driven means for operating on a shoe in a cycle of operations of the machine, of a shoe support movable to present a shoe to said operating means, a device operative by pressure of fluid against it for thus moving the shoe support prior to the starting of the cycle of operations of the machine, a source of supply for the fluid, valve mechanism for controlling the fluid, a member movable by the operator to operate said valve mechanism and thereby render said fluid-operated device effective to move the shoe support, mechanism for controlling the shoe support in the cycle of operations of the machine, and automatic means for disconnecting the valve mechanism from said member to render said fluid-operated device ineffective to control the shoe support in the cycle of operations.
21. In a shoe machine, the combination with power-driven means for operating on a shoe in a cycle of operations of the machine, of a shoe support movable to present a shoe to said operating means, fluid-pressure means for thus moving the shoe support prior to the starting of the cycle of operations of the machine, a member movable by the operator to render said fluid-pressure means operative, mechanism arranged to assume control of the shoe support in the cycle of operations of the machine, and automatic means for rendering said fluid-pressure means inoperative when said mechanism assumes control of the shoe support.
22. In a shoe machine, the combination with means for operating on a shoe, of a shoe support movable to present a shoe to said operating means, fluid-pressure means for thus moving said shoe support, a member movable idly by said fluid-pressure means, and a spring for thereafter moving said member reversely and for thereby imparting a return movement to the shoe support.
23. In a shoe machine, the combination with means for operating on a shoe, of a jack mounted for swinging movement to present a shoe to said operating means, a device operative by pressure of fluid against it for thus swinging the jack, a bell-crank lever movable by said device, and a spring for thereafter moving said bell-crank lever reversely and for thereby initiating return movement of the jack.

JACOB C. JORGENSEN.
